REFRIGERATING APPARATUS

Ralph K. Miller, Dayton, Ohio, assignor to General Motors Corporation, Dayton, Ohio, a corporation of Delaware

Application August 13, 1938, Serial No. 224,786

11 Claims. (CL 62—89)

This invention relates to refrigerating apparatus and more particularly to household refrigerators.

Household refrigerators have generally been provided with a single evaporating means located in the upper portion of a food storage compartment for cooling the food storage compartment by the circulation of air in contact with the walls of the evaporating means as well as for freezing ice in ice trays provided on shelves in the evaporator. This construction was economical and provided satisfactory ice freezing along with a somewhat better food preserving ability than the ice box which it had replaced. However, for certain foods such a refrigerator does not provide satisfactory food preservation because the humidity is not kept sufficiently high, the circulation of air is sometimes too rapid, and the temperatures are often not kept sufficiently low to preserve foodstuffs in such a manner as to keep them in a fresh condition both as to appearance and taste.

Attempts have been made to separate the refrigerator cabinet into two compartments and to provide separate refrigerating means for each compartment, but all such systems have been relatively complicated and sufficiently high in cost to prevent their sale in large quantities in competition with the older styles of household refrigerators. Such a style of two compartment refrigerators would require such extensive manufacturing changes as to make the initial cost of manufacture too high.

It is therefore an object of my invention to provide a simplified, easily manufactured form of household refrigerator in which means are provided for satisfactorily preserving different types of foods, particularly fruits and vegetables.

It is another object of my invention to provide a household refrigerator which may be provided with a high humidity compartment employing substantially all the parts of a conventional household refrigerator.

It is still another object of my invention to provide a household refrigerator having a plurality of compartments which may be adjustable in size and which may be maintained at either different humidities or different temperatures, or both different temperatures and different humidities.

It is still another object of my invention to provide a simplified, easily manufactured form of household refrigerator in which a compartment is provided which is cooled by cooling the walls of the compartment.

It is a still further object of my invention to provide an improved means for cooling the outside of the inner walls of the food compartment by a

simple form of secondary refrigerant system made of plain tubing which may be applied to the walls after the inner walls are coated with porcelain.

It is still another object of my invention to provide a household refrigerator in which the primary evaporator may be removed without disturbing the secondary refrigerant circuit which it cools.

Further objects and advantages of the present invention will be apparent from the following description, reference being had to the accompanying drawings, wherein a preferred form of the present invention is clearly shown.

In the drawings:

Fig. 1 is a perspective view looking at the rear of a household refrigerator cabinet having its rear wall and insulation removed;

Fig. 2 is a fragmentary sectional view taken along the line 2—2 of Fig. 1;

Fig. 3 is a vertical sectional view through the refrigerator cabinet shown in Fig. 1; and

Fig. 4 is a bottom view of the evaporator shown in Figs. 1 and 3.

Briefly, I have shown a refrigerator cabinet of the household type in which the evaporator is suspended within the food compartment and the motor-compressor and condenser are located in the machine compartment beneath the food compartment. The evaporating means is generally of a b-shape type with shelves for ice trays and clamped to the bottom of the evaporator is a U-shaped portion of a secondary refrigerating circuit formed of plain tubing which extends out through an aperture through the rear wall of the inner liner member, and extends around the bottom and the lower portions of the three sides of the inner liner member. This secondary circuit of tubing is clamped to the outside of the inner liner member and is fastened to it and held in place by an asphaltic compound which is poured onto the secondary circuit and the adjacent portions of the inner liner in a molten condition. A glass plate, provided with a rubber gasket seal around its edges, divides the food compartment into a lower high humidity compartment and an upper low humidity compartment which contains and is cooled directly by the primary evaporating means.

Referring now to the drawings and more particularly to Figs. 1 and 3, there is shown a household refrigerator having the sheet metal outer walls 20 which extend continuously around the front and the sides of the cabinet and which are connected at the rear of the cabinet by another sheet metal member 22. The cabinet is also provided with an upper outer sheet metal member 55

24 above the food compartment and a lower outer sheet metal member 26 below the food compartment beneath which there is provided a machine compartment 28. The cabinet is provided with 5 an ornamental top 30 which rests on top of the cabinet. Within the outer sheet metal walls there is provided a box-shaped inner liner member 32 having an open side facing the front and connected by a breaker strip 34 to the edges of a flanged 10 door opening in the front portion of the outer sheet metal wall 20. This flanged opening is closed by an insulated cabinet door 36. The inner liner member 32 is preferably given a white porcelain coating on the inside and a black porcelain coating on the outside prior to the assembly of 15 any parts thereon and prior to its insertion into the cabinet.

The inner liner member 32 encloses an upper food 20 storage compartment 38 and a lower food storage compartment 40 which are divided by a glass plate 42 which is provided with a rubber metal gasket 44 which extends around the edges of the plate for providing a seal between the glass plate and the walls of the inner liner member 32 as 25 well as between the plate and the inside face of the door 36. This gasket 44 has a curled portion 46 which extends into contact with the inner liner member 32 and upper and lower rubber portions 48 which extend around a metal channel-shaped frame member 50 and are turned into the space between the upper and lower faces of the glass plate 42 within the top and bottom portions of the channel-shaped frame member 50. This construction protects the glass from breakage and 30 provides a simple and efficient seal between the two compartments. The glass provides a certain amount of insulation between the two compartments so that different temperatures as well as different humidities may be maintained in the 35 different compartments. If desired two spaced sheets of plate glass may be used instead of the single sheet 42 of plate glass in order to obtain a dividing plate of greater insulating properties.

The primary evaporator 52 is fastened to the 40 top of the inner liner 32 but is slightly spaced therefrom by the spacers shown in Fig. 3. This primary evaporator 52 is generally of conventional construction and is provided with an upper refrigerated shelf 54 for ice trays as well as second 45 shelf 56 which is not refrigerated and which may be made removable if desired. The bottom 58 of the evaporator 52 also serves as an ice tray shelf. The bottom of this evaporator 52 is not altogether conventional, since it is provided with ducts 60 50 extending from front to rear on each side which connects to the downwardly extending ducts to form a sort of header. These ducts 60 on either side of the bottom, are connected by ducts 62 and 64 which are somewhat in the form of a hairpin 55 but which are connected at the rear of the evaporator between the ducts 60 and 64. There is a considerable portion 66 which is not provided with 60 any refrigerant passages.

In order to provide sufficient refrigeration for 65 the lower compartment 40 and to maintain high humidities therein I have provided a secondary refrigerant circuit formed entirely of plain copper tubing. The copper tubing in the secondary circuit for a 5 cu. ft. cabinet is about 28 to 30 feet 70 long and the major portion is wound about the walls of the lower compartment 40. The copper tubing preferably has an outer diameter of $\frac{1}{4}$ of an inch and a wall thickness of about .035 of an 75 inch. Preferably this secondary circuit operates at a higher temperature than the primary evapo-

rator. For instance, if the primary evaporator is maintained at an average temperature of 20° F. it is desirable that this secondary refrigerant circuit operate at about 35° F.

In order to obtain this temperature of the secondary circuit I have provided a condensing portion 68 of the secondary circuit which is formed so as to fit the space 66 at the bottom of the evaporator between the ducts 60 and 64. This condensing portion 68 includes loops 70 and 72 which 10 are located on each side of the duct 64 and are so formed that the tubing extends along the ducts 60 on each side towards the front of the evaporator and then extends along the duct 64. This secondary system, generally designated by the reference character 74, is altogether independent physically from the primary evaporator 52 except that the portion 68 is clamped to the bottom of the evaporator 52 by four removable clamps all designated by the reference character 76 which are 20 held in place by means of nuts 78 to the bottom of the evaporator. These nuts are threaded on studs or bolts which extend through the non-refrigerated portion 66 upon the bottom of the evaporator. The portion of the secondary refrigerant circuit 74 in contact with the evaporating means is about 42 inches or 44 inches long for this size of refrigerator.

The inlet 80 of the condensing portion 68 is slightly higher than the outlet 82 in order to provide a fall in between the entrance and exit of the condensing portion 68. From the outlet 82 the secondary circuit, in the form of tubing, extends downwardly at an angle of 45° across the back of the cabinet forming the down portion 84 30 to the corner of the inner liner and thence extends downwardly to the bottom of the inner liner forming the down portion 86. At the bottom of the inner liner, the secondary circuit has a bottom portion 88 which extends over to a long 35 vertical clamp having a portion extending beneath the bottom of the inner liner member 32 for clamping the portion 88 to the bottom of the inner liner. The tubing forming the secondary circuit then extends to another clamp 92 upon the 40 opposite side of the cabinet which also has a portion for engaging a loop of the bottom portion 88 of the secondary circuit. The bottom portion is provided with another loop which is clamped by a second clamp 94 upon the side of the inner liner 45 where the clamp 90 is located.

The secondary tubing then extends along the front edge of the inner liner and is turned upwardly and held by the fourth clamp 96 located upon the same side of the inner liner as clamp 92. 50 The secondary circuit then extends entirely around the sides and back of the cabinet in the form of a loop 98 which is held on the sides by the four clamps. The secondary circuit then extends to form a loop 102 upon the opposite side of the 55 cabinet which is also held by the clamps 90 and 94 after which the tube extends upwardly to form a goose-neck trap 104 which insures a unidirectional flow of refrigerant within the secondary circuit and makes it necessary that only gas issue 60 from the portion 102. The secondary circuit is provided with a charging tube 106 upon the 45° portion 84 through which the secondary circuit is charged with a suitable amount of volatile liquid such as difluorodichloroethane of which preferably 70 about 15 ounces is used. When the charging is completed, the charging tube is pinched off and sealed.

The size of the two compartments 38 and 40 may be varied by raising or lowering the divid- 75

ing plate 42. The dividing plate 42 normally rests upon shelf guides 140 which are held in place by screws which also serve to hold the clamping members 90, 92, 94 and 96 against the outer surface of the inner liner member 32. These screws, such as screw 142, are threaded inwardly from the outside through the wall of the inner liner member into the shelf guide 140. Thus by this arrangement the clamping members 90, 92, 94 and 96 serve as backing members for fastening the shelf guides in place as well as for supporting the secondary circuit. The shelf guides 144 and 146 are provided above the shelf guides 140 while shelf guides 148 and 150 are provided beneath the shelf guide 140. The glass plate 42 may be placed upon any one of the shelf guides in order to vary the size of the two compartments. These last two shelf guides 148 and 150 are connected by screws extending through the clamping members and the wall of the inner liner into the shelf guides in a manner similar to that for the shelf guide 140. The shelf guide 148 preferably receives a sliding shelf but it may also be used to support the glass plate 42 when only a small high humidity compartment is desired. The lower shelf guide 150 is intended for supporting the shelf containing a pair of ventilated vegetable drawers, such as are shown and described in the Braeutigam Patent No. 1,774,312, patented August 26, 1930.

In order to provide better heat exchange between the evaporating portion of the secondary refrigerant circuit and the lower portion of the wall of the inner liner after the assembly of the secondary circuit to the outside of the inner liner member 32, the portion of the secondary circuit between the loop 88 and the loop 102 is coated with hot asphalt 100 which is supplied in sufficient quantities so that it completely surrounds

the secondary tubing and the adjacent portions of the inner liner member and so provides better heat transfer between the secondary circuit and the inner liner member as well as holds the secondary refrigerant circuit in place.

The primary evaporator may readily be removed from the cabinet without disturbing the secondary circuit. This is done by removing the clamps 76 at the bottom of the evaporator and by removing the closure plates 112 and 114 of the inner liner member 32 and unfastening a back plate 152 as well as removing a pad of insulation between the rear of the evaporator and the outer plate 152. The outer plate 152 is fastened to the rear wall of the cabinet and sealed thereto by a rubber gasket 154. The supply and return conduits 118 and 120 extending through the back plate 152 are provided with rubber bushings or grommets to seal the aperture through which these conduits pass.

The space between the inner liner member 32 and the outer sheet metal walls is preferably filled with some suitable insulating material 156, such as glass wool. Preferably the portion of the inner liner provided with the secondary refrigerant circuit is coated with heavy wrapping paper prior to its insertion in the cabinet in order to permit easy insertion of the inner liner into the cabinet without disturbing the insulation which is preferably packed in place prior to the insertion of the inner liner. The inner liner member 32 is readily removable through the door opening of the cabinet by removing the screws which fasten the breaker strip to the flange surrounding the door opening. This also requires the removal of the clamps 76 which clamp the

portion 68 of the secondary circuit to the bottom of the evaporating means. Thus merely by unfastening the evaporator from the top wall of the inner liner and by removing the clamps 76 as well as plates at the rear of the evaporator the inner liner member may be removed from the cabinet through the door opening while the primary evaporator 52 may be removed through the opening in the rear wall of the cabinet.

With this construction it is not necessary to use an inert gas in the secondary refrigerant system in order to maintain a temperature differential between the primary evaporator and the secondary evaporator. This is taken care of by limiting the amount of heat transfer between the primary evaporator and the condensing portion 68 of the secondary refrigerant system. However, if desired better heat transfer can be obtained by providing greater contact area between the condensing portion 68 and the bottom of the evaporator, and with such an arrangement an inert gas may be used in the secondary system in order to maintain the desired temperature differential between the primary evaporator and the secondary circuit. Preferably the secondary circuit is always maintained at a temperature above freezing. The primary evaporator normally operates below freezing temperatures in order to freeze ice cubes. Thus this arrangement, the adjacent portions of three sides and the bottom of the inner liner member 32 are cooled to a temperature of about 36° F. Because of this large amount of cooling surface provided for the lower compartment 40, the secondary circuit may operate at a relatively high temperature and yet maintain a low temperature in the compartment 40. The high temperature of the cooling surface makes possible a high humidity.

The inner liner member 32 is provided with an opening 110 in its rear wall adjacent the rear of the evaporator. This opening is provided with a curled edge which supports a set of plates 112 and 114 which close the opening 110. A rubber gasket is provided between the edges of the plate and the edges of the opening 110 and a rubber gasket is also provided between the adjacent edges of the plates 112 and 114. Between the adjacent edges of the plates 112 and 114 there is provided an upper aperture sealed by a rubber grommet 116 through which the liquid supply line 118 and the liquid return line 120 extend to the evaporating means from the motor-compressor-condenser unit provided in the machine compartment.

The motor-compressor-condenser unit comprises a sealed motor-compressor unit 120 which compresses the refrigerant and forwards the compressed refrigerant to a finned natural draft condenser 122 which has its lower end connected to the liquid supply conduit 118 while the return conduit 120 is connected to the inlet of the motor-compressor unit 120. The supply and return conduits 118 and 120 are preferably soldered together a considerable portion of the distance between the motor-compressor-condenser unit and the evaporator to provide a transfer of heat from the supply conduit to the return conduit. The liquid supply conduit 118 is preferably formed of capillary tubing and connects to a restrictor 124 located in the food compartment 38 for controlling the feeding of the liquid refrigerant into the primary evaporator.

The operation of the refrigerating system is controlled by a switch 126 which is located within the confines of the evaporator 52 near the top of the cabinet. This switch 126 has a thermostat 75

bulb 128 which is clamped to the side wall of the evaporator 52 just beneath the upper shelf 54. The control switch 126 is preferably of some form of dual control responsive not only to the temperature of the evaporating means through the medium of the bulb 128 but also responsive to the temperature of the compartment within which the switch mechanism 126 is located. Several examples of such a switch is shown in the 10 Grooms Patent No. 2,101,498, patented Dec. 7, 1937. Such a control controls the operation of the refrigerating apparatus so as to not only maintain the temperature of the evaporating means within certain limits but also tends to 15 maintain the temperature of the compartment 32 within certain limits.

In order to prevent the compartment 32 from becoming too cold and yet providing adequate refrigeration for the lower compartment 40 and 20 for freezing ice, the primary evaporator 52 is provided with shields 130 and 132 located upon opposite sides of the primary evaporator 32 and fastened to the top of the inner liner in a manner somewhat similar to the evaporating means 52. 25 These shields are held spaced from the evaporating means by "Bakelite" spacers 134. The evaporating means is also provided with a rear closure plate 136 and a front door 138 for further reducing the surface available for cooling the 30 compartment 38.

It will be noted that my two compartment refrigerator differs only slightly from the conventional refrigerator in its general construction so that the economy of mass production of this 35 general type may be used for this two compartment refrigerator. In general only the secondary refrigerant circuit, the glass plate 42 and the shielding of the evaporator means have been added to the conventional refrigerator. This 40 form of refrigerator makes it possible to provide a cold atmosphere having relatively high humidity in the compartment 40 and a considerably drier atmosphere in the compartment 38. The cooling of the compartment 40 through the secondary refrigerant circuit which surrounds the 45 walls of the inner liner particularly aids in maintaining a high humidity in this compartment and prevents dehydration because the heat leaking through the insulation is withdrawn by the secondary circuit before it reaches the air in the 50 compartment 40. The rate of air circulation within the two compartments is also less than has been customary.

The front lower lip of the inner liner member is 55 provided with a ridge 160 for preventing any moisture which might collect on the bottom of the inner liner from running out the door of the cabinet when the door is open. It will be noted that when the door 36 is open access is readily had 60 both to the upper compartment 38 and the lower compartment 40. The glass plate 42 assures ready and complete visibility to the lower compartment 40. Thus I have provided a two compartment refrigerator which is simple, practical, 65 economical and very effective for the preserving of foods, because of the cool moist compartment 40.

While the form of embodiment of the invention as herein disclosed, constitutes a preferred form, 70 it is to be understood that other forms might be adopted, all coming within the scope of the claims which follow.

What is claimed is as follows:

1. Refrigerating apparatus including a cabinet 75 provided with a metal inner liner member, a

refrigerant evaporating means entirely within said inner liner member, a portion of said inner liner member being provided with means forming a secondary refrigerant circuit, said means forming a secondary refrigerant circuit having a closed 5 metal walled containing portion extending forwardly from the rear wall of the inner liner member, means for clamping said metal walled containing portion to a portion of the surface of the evaporating means, and a movable partition 10 within said inner liner separating the evaporating means and the adjacent interior of the inner liner from the interior of said portion of said inner liner provided with the secondary circuit.

2. Refrigerating apparatus including a cabinet 15 provided with a metal inner liner member, an evaporating means entirely within said inner liner member, means forming a secondary refrigerant circuit including tubing having portions extending around a portion of the outside of said inner 20 liner member, means for clamping and holding said tubing in intimate thermal contact with the exterior of said inner liner member, said means forming a secondary circuit having another portion 25 extending into the interior of said inner liner into intimate thermal contact with said evaporating means, and a movable partition within said inner liner separating the evaporating means and the adjacent interior of the inner liner from the interior of said portion of said inner liner 30 provided with the secondary circuit.

3. Refrigerating apparatus including a cabinet provided with an inner liner member, a movable dividing wall dividing the interior of said inner liner into two compartments, a refrigerant 35 evaporator located entirely in one of said compartments in said inner liner member spaced from and outside the plane of the dividing wall for preventing direct contact with the atmosphere in the other compartment, means forming a 40 secondary refrigerant circuit having a portion in heat exchange relation with the outside of the portion of the inner liner member which surrounds the other compartment, said means forming a secondary refrigerant circuit having another portion in heat exchange relation with said 45 refrigerant evaporator, said dividing wall being movable to change the size of said compartments.

4. Refrigerating apparatus including a cabinet provided with a single unitary inner liner member, 50 a movable dividing wall dividing the interior of said inner liner into two compartments, a refrigerant evaporator located in one of said compartments in said inner liner member spaced from and outside the plane of the dividing wall for preventing direct contact with the atmosphere in the other compartment, means forming a secondary refrigerant circuit having a portion in heat 55 exchange relation with the outside of the portion of the inner liner member which surrounds the other compartment, said means forming a secondary refrigerant circuit having another portion in heat exchange relation with said refrigerant evaporator, said dividing wall being transparent.

5. Refrigerating apparatus including a cabinet 65 containing an inner liner member, a refrigerant evaporator within said inner liner member, said inner liner member being provided with an aperture adjacent said evaporator, tubing containing 70 a secondary refrigerant having a portion in contact with the outer surface of said inner liner member, said tubing extending through said aperture into the interior of said inner liner member into contact with a surface of said evaporator, 75

and means for clamping said tubing to the outer surface of said inner liner member.

6. Refrigerating apparatus including a cabinet containing an inner liner member, a refrigerant evaporator within said inner liner member, said inner liner member being provided with an aperture adjacent said evaporator, tubing containing a secondary refrigerant having a portion in contact with the outer surface of said inner liner member, said tubing extending through said aperture into the interior of said inner liner member into contact with a surface of said evaporator, and means for clamping said tubing to said surface of said evaporating means.

15 7. Refrigerating apparatus including a cabinet, a single unitary inner liner member within the cabinet, an evaporator within the cabinet, said inner liner member being provided with a large aperture adjacent the rear of the evaporator to permit removal of the evaporator, said inner liner member being provided with means forming a secondary refrigerant circuit, said means forming a secondary refrigerant circuit being provided with a portion extending through said large aperture 25 into heat exchange relation with the evaporator.

8. Refrigerating apparatus including a cabinet provided with box-shaped walls enclosing a compartment to be kept cool, means for cooling said compartment with diminished convection currents, high humidity and reduced dehydration comprising refrigerating means for reducing temperatures of the inner faces of the bottom and three distinct vertical wall portions of said box-shaped walls below the temperature of the atmosphere within the compartment but above 30 water freezing temperatures.

35 9. Refrigerating apparatus including a cabinet provided with box-shaped walls enclosing a compartment to be kept cool, means for cooling said compartment with diminished convection cur-

rents, high humidity and reduced dehydration comprising refrigerating means for reducing temperatures of the inner faces of the bottom and three distinct vertical wall portions of said box-shaped walls below the temperature of the atmosphere within the compartment but above water freezing temperatures, said refrigerating means including means for first feeding a cooling medium into heat exchange relationship with said bottom wall portion and thence into heat exchange relationship with said three distinct vertical wall portions. 10

10 10. Refrigerating apparatus including a cabinet provided with box-shaped walls enclosing a compartment to be cooled, a movable dividing wall 15 means dividing said compartment into a plurality of sub-compartments, a primary refrigerating means spaced from and outside the plane of said movable means for creating water freezing temperatures in one of said sub-compartments, and 20 means for cooling a second sub-compartment with diminished convection currents, high humidity, and reduced dehydration comprising means including a secondary circuit cooling means connected in heat transfer relationship with said 25 primary refrigerating means for cooling the inner faces of the bottom and three distinct vertical wall portions of said second sub-compartment to temperatures below the temperature of the atmosphere of said second compartment but above 30 water freezing temperatures.

11. The method of producing refrigeration and diminishing convection currents, increasing humidity and reducing dehydration within a metal-lined storage compartment which comprises cooling the bottom and three distinct vertical wall sections of said metal lining by a cooling medium maintained above water freezing temperatures. 35

RALPH K. MILLER. 40
